UNITED STATES PATENT OFFICE.

ERNEST YEOMAN ROBINSON, OF MANCHESTER, ENGLAND, ASSIGNOR TO METROPOLITAN-VICKERS ELECTRICAL COMPANY LIMITED, OF LONDON, ENGLAND, A BRITISH JOINT-STOCK COMPANY.

VACUUM TUBE.

Application filed November 27, 1922, Serial No. 603,715, and in Great Britain December 6, 1921.

This invention relates to vacuum electric discharge tubes having electron emitting cathodes therein such, for example, as the so-called thermionic rectifiers and valves 5 used in wireless telegraphy and telephony and has for its object to provide an improved construction and arrangement of vacuum tube the envelope of which contains an ionizable rarefied atmosphere but in 10 which ionization is eliminated or reduced to a minimum in a simple and effective manner.

My invention comprises the combination with a cathode providing a concentrated source of electrons and an anode in close 15 proximity thereto so that the inter-electrode space is small, of means for confining the space current to the said inter-electrode space.

My invention further comprises the provision 20 of screens or shields for confining the space current to the said inter-electrode space.

My invention further comprises the confining of the space current to the inter-electrode space by reducing the activity for the 25 emission of electrons of those portions of the cathode from which electron currents would normally tend to pass outside the inter-electrode space.

30 My invention further comprises the improved details of construction and arrangement hereinafter described and claimed.

The cathodes of valves constructed according to this invention are such that the 35 electron source is concentrated. Preferably, the active surface of the cathode is continuous. It may consist of a sheet of metal, such as tungsten, which may be flat or curved to any desired shape. It may, for example, be formed into a cylindrical tube and be heated by a thermionic discharge 40 from an auxiliary cathode disposed within the tube; or it may be heated by radiation from a heated filament similarly disposed. If the cathode be a flat sheet, then two such sheets may be employed with the auxiliary 45 cathode or heating filament between them.

A cathode, the electron source of which is 50 concentrated and which approximates in action to a cathode whose surface is continuous, may be constructed from a coiled filament whose turns are closely spaced. The cross section of the filament may preferably be rectangular, which section permits of

closer spacing of the filament turns and provides a closer approximation to a cathode whose surface is continuous.

The anode is preferably of a similar shape to the cathode and is so mounted that there is a small gap which is uniform over the 60 active face of the cathode, between the anode and cathode.

In valves constructed according to present practice, the amount of ionization is mainly determined by the electrons which travel by the fringing paths because, firstly, the ionization is proportional to the length of the path and, secondly, the presence of gas (and hence of ionization) reduces the impedance of the fringing paths to the space current 70 more than it reduces the impedance of the direct paths so that a larger proportion of the space current flows by the fringing paths when gas is present. The effect is cumulative and hence in a "soft" valve the main 75 portion of the current is carried along the fringing paths, which are paths of the longest possible length and so the degree of ionization is mainly determined by the maximum length of path which is possible 80 in such a valve. Now in accordance with my invention, the space through which the space current flows is reduced to a minimum by being limited (as hereinafter more fully described) to the inter-electrode space in 85 which the number of gas molecules available for ionization is limited. The electrons are highly concentrated in this space and so molecules of gas may usually experience more than one collision before they reach 90 the cathode and give up the charge they acquired at the first collision. At the second collision, the charge on these ions may be neutralized so that an increase of space current will not result in an increase of ionization for although more molecules are ionized when the space current increases, more ions are neutralized before they reach the cathode. I have found that with a vacuum 95 tube constructed in accordance with this invention, the pressure of the residual gas in the tube during operation may be many times that permissible in valves constructed in accordance with present practice before ionization becomes appreciable.

The space current may be confined to the inter-electrode space by different means such as by suitably placed screens or shields which

prevent by actual mechanical screening or by electrostatic screening, or by both mechanical and electro-static screening, the flow of space current outside the limits of the inter-electrode space. Or the edges and other portions of the cathode from which electrons would normally pass outside the inter-electrode space may be kept at a sufficiently low temperature that they do not emit an appreciable amount of electrons. This may be effected by arranging that either less heating current is supplied to the said portions of the cathode or the said portions have a large and efficient heat radiating surface. Or a combination of these means may be employed. A further means of confining the space current to the inter-electrode space consists in making the portion or portions of the active surface of the cathode from which the electrons are emitted which tend to flow by the fringing paths to the anode, of a material which has a low electron emission co-efficient. Thus, with a cylindrical tubular cathode having its active surface on the outside, the tube may be made of tungsten and the outside surface coated with thorium, the tube being operated at a temperature at which the electron emission from tungsten is negligible. When the space current is thus confined, the inactive portions of the cathode act as electrostatic screens confining the space current to the inter-electrode space. Those specific embodiments wherein the boundaries of the cathode have relatively reduced activity for electron emission form the subject-matter of a continuing application Serial No. 96,050, filed March 19, 1926.

The accompanying explanatory diagrams illustrate the application of my invention.

Figures 1 and 2 illustrate the effect of decreasing the gap in an ordinary diode.

Figures 3 to 9 illustrate several applications of my invention.

Referring in the first place to Figure 1, in which *a* is a filament cathode and *b* a tubular anode, it will be seen that electrons will travel along direct paths as *c* and indirect or fringing paths as *d* and *e*. The length of the path *e* will be limited by the valve envelope (not shown). The ratio of the space current which flows along paths such as *c* to that which flows along fringing paths such as *d* and *e* is proportional to the ratio of the direct electrostatic flux to the fringing flux. It will thus depend on the gap between the electrodes and the area of the electrodes. If the gap between the electrodes be reduced, the ratio of the direct flux to the fringing flux will be increased, but the fringing flux will still remain. As previously stated, if ionization be present, the space current tends to flow more and more by the fringing paths. The amount of ionization in a valve is determined mainly by the length of the longest path.

Figure 2 shows a valve tube in which the anode consists of two parallel plates with a filament cathode between them. Considering a single filament, the direct and shortest path for electrons is at *f* whilst fringing currents will flow at *g* and *h*. The latter path is relatively long and when the gap between the electrodes is of the order say of 1 cm. it will not be appreciably reduced by shortening the gap. A reduction in gap between the electrodes will, when the gap is small, have less effect in reducing ionization with this arrangement of electrodes than with the arrangement shown in Figure 1.

Figures 3 and 3^a illustrate the application of the present invention to a rectifier having a cylindrical cathode. The latter has the reference letter *i* and constitutes a concentrated source of electrons which is an essential feature of my invention. It is heated by a discharge from an auxiliary filament cathode *j*. *i* is placed inside the cylindrical anode *k* which is mounted coaxially with and at a very small distance from the cathode. At the opposite open ends of the cathode *j*, I provide shielding screens *m* and *n* which may be metal discs of as large a diameter as possible (without touching the anode) in order that they may exert a maximum screening effect. The screens *m* and *n* are, in the example illustrated, insulated from the main cathode *i* and electrically connected to the auxiliary cathode *j* so that they are at negative potential with respect to the cathode. If the gap between the discs or shields and anode is small, the discs may be made thin, their thickness being increased with increase of the said gap. The cathode is supported by three stems *o* which pass through the shield *m*. The auxiliary cathode support *p* passes through the shield *n*.

The shields *m* and *n* prevent electrons from the edges and inside of the tube *i* from flowing to the anode *k* and confine the electrons flowing from the active surface of the cathode *i* (in this case the outer surface of the tube), to the inter-electrode space. The cathode is heated by a thermionic discharge from the auxiliary cathode *j*, in this case a closely coiled wire helix (which may preferably consist of the same material as the cathode) in order to provide a device having a concentrated source of electrons and a small inter-electrode space between the cathode and the auxiliary cathode. The auxiliary cathode *j* is heated by an electric current, and the main cathode is made positive to the auxiliary cathode so that a space current flows from the latter to the main cathode, which space current heats the cathode in a manner itself well known. The heating space current is confined to the inter-electrode space between the auxiliary cathode and the cathode, and fringing currents are prevented by the shields *m* and *n*.

and *n* which thus serve a dual purpose. In the example shown, the auxiliary cathode is supported by the stems *p* and *r*. The shields are attached to the stem *p* which provides a convenient method of charging them negative to the cathode. Alternatively, the shields *m* and *n* may be insulated. They may still be supported by the stem *p* but may be affixed thereto by means of insulating beads, constructed of a material such as, for example, quartz, in a similar manner to that by which the grid is supported as herein-after described with reference to Fig. 7. In this case, they must be attached to an extension of the stem *p*, which extension is so designed that at the point of attachment of the insulating beads, it is relatively cool.

If desired, the cathode may be heated entirely by heat radiated from a filament *g*, the shields being so designed or arranged that they do not become heated to a temperature at which they emit electrons appreciably, this result being obtained if the surface area of the shields is sufficiently large as can be determined by experiment.

Where tubular electrodes are employed the shield may consist of a tube whose length is preferably at least twice its diameter, and whose diameter is as large as possible without the shield touching the anode.

Figure 4 shows an example of the application of this invention to a rectifier having plane electrodes. For clearness, the anode is omitted in the drawing. The cathode consists of two plates of suitable material such, for instance, as tungsten, mounted parallel with and facing each other. They are heated by a discharge from the auxiliary cathode formed by the heated filament *t*. This filament is held taut by the spring supports *u*, and the space between the adjacent layers of this filament is reduced to as small a value as possible, in order to provide a concentrated source of electrons, so that the heating space current may flow without producing appreciable ionization. The space current from the cathode to the anode is confined to the inter-electrode space by the shield *v* which is placed round the edges of the cathode. It is separated by a small gap from the cathode, in order to insulate it; it is preferably joined electrically to the negative end of the auxiliary cathode. The shield contains slits such as *w* which permit the filament supports to pass through. This shield also acts as a shield to the heating space current and confines it to the inter-electrode space between the auxiliary cathode and the cathode. The anode consists of two metal sheets (not shown) mounted parallel to and facing the plates *x* and *y* and is separated from them by a small gap. The cathode plates may be heated by radiation from the filament in lieu of a discharge from the auxiliary cathode in a similar man-

ner to the case when cylindrical electrodes are employed.

Figure 5 shows an application of the invention using a filament cathode. The anode is shown at *k*; the cathode *i* consists of a closely spaced helix of tungsten wire supported by the leading wire *r*, the other end being attached to the shielding screen *m* which may preferably consist of a tungsten or molybdenum disc. This screen is fastened to the rod *p*. The shielding screens are shown at *m* and *n*, the screen *n* being attached to the supporting rod *p* and pierced to allow the entry of the tungsten wire attached to the leading wire *r*. The cross section of the filament may be circular or rectangular.

Figure 6 shows an application of the invention to a valve having cylindrical electrodes which is more able to stand the high potentials. In Figure 6, the anode is shown at *k*. The filament *i* is wound in a zig-zag path, each turn lying approximately on the surface of an imaginary cylinder and substantially parallel with the axis of the latter and the turns are supported at each end by spring spiders *2*, each of which is constructed of wire fused into an insulating bead *3* such as, for instance, quartz. In the figure the filaments and the supporting spiders at one side of the plane of the section are shown. The quartz beads *3* are supported by the metal rod *p*. The adjacent layers of the filament are arranged as close as practicable to each other. The screens are shown at *m* and *n*. They are supported by and connected to the rod *p*.

Figures 7 and 7^a show an example drawn to an enlarged scale of the application of this invention to a three electrode tube having cylindrical electrodes where the cathode is heated by a thermionic discharge from a heated auxiliary filament cathode. The filament and cathode of this valve are constructed substantially as described with reference to Figure 3. The screens are in the form of discs *m* and *n* attached to the stem *p*. The disc *n* is pierced to allow the entry of the lead in wire *r*, and the cathode supporting stems *o*. The grid is composed of substantially parallel wires *s* supported by the two rings *6* and *7*. In the case shown, the grid wires are held taut by the springs *8*. The annular ring *6* is slotted to permit the grid wires to pass through to the supporting springs. The rings *6* and *7* are supported by the stems such as *9*, fused into the insulating beads *10*. The annular rings *6* and *7* serve as auxiliary screens to confine the space current to the inter-electrode space, and they are preferably mounted so that the gap between them and the anode is as small as possible.

Fig. 8 shows an application of the invention to a valve employing a cathode having

its outside surface coated with thorium and wherein the main space current is confined to the inter-electrode space by making the boundaries of the cathode of a material 5 which has a low electron-emission coefficient. In the construction shown in this figure, i' represents the main cathode which comprises a cylindrical tube composed of tungsten the outside surface of which is provided with a 10 coating i^2 of thorium which coating however terminates short of the ends of the tube, as shown, so that the tungsten composing the tube will be exposed at these boundaries of the cathode. The auxiliary cathode j' , and 15 cylindrical anode k' correspond with the similarly designated parts shown in Fig. 3, the shields m' and n' prevent electrons from the inside of the main cathode i' from flowing to the anode k' , and the thoriated outside 20 surface of the main cathode i' is opposite to and arranged within the anode which is spaced from the active surface of the main cathode substantially as described in connection with Fig. 3. In using a valve made 25 in accordance with this embodiment of the invention, it is operated at a temperature at which the electron-emission from the un-coated tungsten ends or boundaries of the main cathode is negligible. These inactive 30 boundaries of the cathode thus act as electro- static screens which confine the space current between the cathode and anode to the inter-electrode space.

Fig. 9 is a diagrammatic view showing an 35 application of the invention to a valve wherein the end portions of the cathode are kept at a sufficiently low temperature to avoid appreciable electron-emission therefrom and to thereby confine the space current to the inter-electrode space. In this 40 instance is shown a straight filament cathode i^3 and a tubular anode k^2 which is preferably cylindrical and of small diameter. The cathode is attached to two co-axial heat radiating 45 lead-in wires r' and it is only so much longer than the anode k^2 that the ends of the cathode are cooled by the lead-in wires r' to such an extent that the electron-emission from said end portions of the cathode is 50 small or even negligible compared with that from the main or central portion of the cathode. The temperature distribution along the cathode is typically indicated by the curve X , and the corresponding electron-emission 55 is indicated by the curve Y . The portions of the cathode from which electrons would normally pass outside the inter-electrode space are thus kept at a sufficiently low temperature that they do not emit an appreciable amount of electrons.

In the construction of vacuum tubes according to this invention, the best results with a given type of cathode and shields and a constant gas pressure, are obtained 60 when the inter-electrode space is smallest.

For a tube to have hard characteristics, the gap must be reduced as the pressure of the residual gas is increased; it must also be reduced as the molecular weight of the residual gas is increased. The gap necessary to give 70 a tube of hard characteristics will be very much less in the case of a tube containing mercury vapour than in the case of a tube containing say helium. Generally, it is preferable that the length of the gap be reduced 75 to the smallest practicable value, which length will be limited by constructional difficulties. It is possible to obtain a smaller gap using a tube heated by, say, a thermionic discharge than when a filament is used. Better 80 results are obtained when both the electrodes are allowed to become incandescent. When the device is used with both electrodes incandescent, rectification must be effected by making the anode at a sufficiently low temperature 85 so that it will not allow an inverse current to flow.

The use of this invention permits of the construction of vacuum tubes having hard characteristics in which the residual gas 90 pressure is comparatively high. The advantages resulting from this will be obtained in several ways. Firstly, with ordinary vacuum tubes, it is necessary to evacuate those intended for use as rectifiers or oscillators 95 to a high vacuum of, say, a few hundredths of a micron, and further it is necessary by a lengthy and laborious process to heat treat the electrodes, the valve envelope and the component parts to get rid of all absorbed 100 gases, so that these may not be evolved during operation of the tube. Not only is this an expensive process, but as the size of the tube is increased it becomes increasingly difficult to effect properly so that a limit is 105 set to the size of the valve tube which may be constructed. When vacuum tubes are constructed according to this invention, the heat treatment need not be so thorough since the pressure of the gas in the tube may be 110 allowed to rise to comparatively high values before the tube becomes soft, and as a result the cost of production of such valves is lessened; it also becomes possible to construct 115 valves of larger sizes. Secondly, owing to 120 the amount of gas evolved during operation, it is not practicable to employ ordinary vacuum tubes having metallic containers or water cooled anodes. By the use of this invention, such devices become practicable. Thirdly, it is not practicable to evacuate an 125 ordinary valve tube during operation by means of a vacuum pump unless a liquid air or like trap is interposed between the vacuum tube and the pump owing to the diffusion of vapour from the pump into the tube. For instance, with a mercury pump, mercury vapour will diffuse into the valve tube and will have a pressure of about 1 micron at atmospheric temperature. Mer- 130

ctiry vapour at this pressure would produce blue glow at anode voltages of 20 to 30 volts in valves constructed according to present practice. By the use of this invention, vacuum tubes may be exhausted during operation by a vacuum pump such, for instance, as a mercury vapour pump without a low temperature trap being interposed between the pump and the vacuum tube; or alternatively where extra high voltages are applied to the tube a moderately cold trap, for example, brine and ice may be employed.

I claim:—

1. In a vacuum electric discharge tube having an envelope containing an ionizable rarified atmosphere, an anode, a thermionic cathode mounted within the anode, said anode and cathode being so closely spaced that the inter-electrode electron paths are of less length than the mean free path in said atmosphere and are sufficiently short to give the tube "hard" characteristics which atmosphere in a longer gap would be ionized and would give the tube "soft" characteristics, and means at the boundaries of said cathode exposed to the space outside of the inter-electrode space to substantially confine the electrons to said inter-electrode space.

2. In a vacuum electric discharge tube having an envelope containing a rarified ionizable atmosphere, an anode, a cathode mounted within the anode and capable of emitting electrons only when heated above normal temperature, said cathode and anode being spaced sufficiently closely to provide paths for the electrons which are of less length than the mean free path in said atmosphere and are sufficiently short to give the tube "hard" characteristics, the pressure of said atmosphere being so high that the electrons in a longer gap would produce gaseous ionization in such atmosphere and would give the tube "soft" characteristics, and shields at the ends of the cathode for

substantially confining the electrons to the 45 inter-electrode gap.

3. In a vacuum electric discharge tube having an envelope containing an ionizable rarified atmosphere, an anode, a thermionic electron-emitting cathode mounted within 50 the anode, said electrodes having their active surfaces so disposed and closely spaced as to provide inter-electrode electron paths which are of less length than the mean free path in said atmosphere and are sufficiently 55 short to give the tube "hard" characteristics, which atmosphere in a longer gap would be ionized by such electrons and would give the tube "soft" characteristics, and electrostatic shields adjacent to the ends of the cathode 60 to substantially confine the electrons to said inter-electrode space.

4. In a vacuum electric discharge tube having an envelope containing an ionizable rarified atmosphere, a substantially cylindrical anode, a substantially cylindrical thermionic electron-emitting cathode mounted within the anode and having its ends arranged within the ends of the anode, said electrodes having their active surfaces sufficiently 65 closely spaced to provide inter-electrode electron paths all of which are shorter than the mean free path in such atmosphere and are sufficiently short to give the tube "hard" characteristics, said atmosphere being at such pressure as would cause impact ionization in a longer gap and would give the tube "soft" characteristics, and shields mounted within the anode and at the respective 70 ends of the cathode for preventing the electrons escaping from said inter-electrode space and of following paths outside said space of sufficient length to cause ionization of said atmosphere outside said space and to give the tube "soft" characteristics. 75

In testimony whereof I have signed my name to this specification.

ERNEST YEOMAN ROBINSON.
